CRANKCASE VENTILATOR DEVICE

Harold D. Daigh, Rolling Hills Estates, and Rondo H. Patzig, Bellflower, Calif., assignors to Richfield Oil Corporation, Los Angeles, Calif., a corporation of Delaware

Filed Aug. 12, 1963, Ser. No. 301,483
19 Claims. (Cl. 123—119)

This application is a continuation-in-part application of Serial No. 262,936, filed March 5, 1963, and now abandoned. The present invention relates to an internal combustion engine and, more particularly, relates to a crankcase ventilating system for an internal combustion engine wherein a flexible valve is positioned in a conduit adapted to recycle blowby from the crankcase to the induction system.

A valve device for controlling the recycle of crankcase blowby into the induction system of an internal combustion engine is described in U.S. Patent No. 3,077,871, issued February 19, 1963, to Harold D. Daigh on a "Crankcase Ventilating System for Internal Combustion Engines." The valve device described in this patent is adapted to open in response to crankcase pressure buildup and to close in response to intake manifold vacuum, thereby constricting the blowby conduit leading from the crankcase to the intake manifold to the passage of blowby when intake manifold vacuum is high, but opening the conduit at higher throttle settings when the crankcase blowby is sufficient to exert pressure on the tubular valve. In order for the aforesaid valve to function properly, it is desirable to keep the "open" ends of the conduit to which the tubular valve is connected, in substantially axial alignment so that the tubular valve can open and close, as described above.

In order for the aforesaid tubular valve to open properly, it is necessary to position the valve between the open conduit ends under a slight tension. Since a section of the tubular valve is preformed closed, the valve readily closes in response to intake manifold vacuum, notwithstanding the slight tensioning of the tubular valve.

It is, therefore, an object of the present invention to provide a support device for holding in substantially axial alignment the open ends of a conduit adapted to pass blowby fumes from the crankcase to the induction system of an internal combustion engine through a tubular valve connecting said conduit open ends.

It is a further object of the present invention to provide means for preventing crankcase explosions caused by the passage of combustible mixtures through the recycle conduit extending between a crankcase recycle valve and an intake manifold.

It is also an object of the present invention to provide a means for varying the tension on a tubular valve positioned between the open ends of a conduit adapted to pass blowby fumes from the crankcase to the induction system of an internal combustion engine.

It is a further object of the present invention to provide means for maintaining tension at a predetermined setting on a flexible valve positioned between the open ends of a conduit adapted to pass blowby fumes from a crankcase to an induction system.

Other objects and a more complete understanding of our present invention may be had by reference to the following specification and the appended claims when taken in conjunction with the following drawings, wherein:

FIG. 1 shows in partial section an internal combustion engine utilizing a flexible valve in the conduit extending between the rocker arm and the induction manifold, with a support frame of our present invention utilized to position and tension the valve;

FIG. 2 shows in partial section an enlarged elevation showing a support frame device of our present invention

2

in its preferred form with the tubular valve in closed position;

FIG. 3 shows in partial section an enlarged view of a support valve of our present invention with the recycle valve in open position;

FIG. 4 shows a sectional view taken on section 4—4 of FIG. 2;

FIG. 5 shows in partial section an enlarged view of a modified form of our present invention;

FIG. 6 shows in partial section an enlarged view of a further modification of the support means of our present invention;

FIG. 7 shows an enlarged view of another modification of our present invention wherein a one-way valve is incorporated in the valve support means;

FIG. 8 shows a protective cover over the recycle valve of FIG. 7;

FIG. 9 illustrates an additional modification of the apparatus shown in FIG. 2.

The present invention involves an internal combustion engine having a conduit 16 provided externally between the crankcase 26 and the induction system manifold 28. A valve 10 is positioned in a break in the conduit to control the recycle of blowby fluids from the crankcase to the induction system. The present invention involves means for supporting valve 10. For convenience, the conduit is shown as extending from the rocker arm cover, although the conduit could be connected to any portion of the engine which is in communication with crankcase pressure.

Referring generally to the drawings, the tubular valve 10, described more fully in U.S. Patent No. 3,077,871, is positioned at the break between the ends 12 and 14 of the conduit 16 extending between the crankcase and the induction system of the internal combustion engine shown in FIG. 1. The support and tensioning frame of our present invention, in its preferred form, is shown in FIGS. 2, 3 and 4, and consists of a pair of support members 18 and 20 positioned on the conduit ends on either side of the conduit break and fastened to their respective conduit ends. Post members 22 and 24 extend between and connect the support members and provide a rigid connection between the support member and means to vary the distance therebetween in accordance with our present invention. Although two post members are shown, it is readily apparent that one post member would suffice.

In order for the tubular valve 10 to function properly, it is desirable to have the conduit ends 12 and 14 held in substantial axial alignment. This may be accomplished preferably by affixing the support members 18 and 20 to the conduit in any convenient manner, as, for example, by welding as shown in FIG. 2 or by using set screws as shown in FIG. 7, in which event the support frame may be removed from the conduit. The support member 20 is threadably engaged by the posts 22 and 24 and the ends 34 and 36 of the posts 22 and 24, respectively, are rotatably disposed within the support member 18 so that the distance between the conduit ends 12 and 14 may be varied by rotating the posts 22 and 24. Increasing the distance between the conduit ends 12 and 14 effectively tensions the tubular valve 10 since the ends of the tubular valve are held onto the conduit ends by clamps 38 and 40 or by any convenient means, such as gluing, clamping, etc.

The device of our present invention is preferably installed by preassembling the support means and valve on the conduit and cutting the conduit 16 to fit the connectors 44 and 46 of the rocker arm cover and intake manifold, respectively, after which the tension of the valve can be set as desired to give optimum operability. As the elastic characteristics of the material of the tubular valve 10 deteriorate, our invention makes it possible to change the distance between the conduit ends and

thereby maintain tension substantially constant on the tubular valve 10. Springs 56 and 58 are positioned around posts 22 and 24, respectively, between support members to maintain a constant tension on the valve as the flexible valve material "relaxes" with age. Thus, the tension set on the valve 10 by adjusting threaded posts 22 and 24 against the springs remains substantially at the predetermined valve over a longer period of time without adjustment.

When provision is made for the passage of a small quantity of blowby through the tubular valve at all times, such as with a valve having a small opening 89 at closed position (FIG. 4), it may be desirable to provide a line 82 from the air filter 84 to crankcase 26 and set valve 10 to impose a slight vacuum on the crankcase at all times to thus pull "clean air" from the clean side of the air filter into the crankcase. The provision for clean air in the crankcase is believed to reduce sludge formation in the crankcase.

In order to prevent backfire from carrying an explosion into the crankcase, a one-way valve, such as swing check valve 86, is positioned in the recycle line between the valve 10 and the intake manifold. This one-way valve may also be incorporated in the valve support frame as shown at 88 in FIG. 7.

FIG. 5 shows a modified form of our present invention wherein a spring 48 is helically disposed around the tubular valve 10 to maintain a predetermined tension on the valve.

Another modification of our present invention is shown in FIG. 6 providing the posts 22 and 24 with shoulders 42 which bear against the support member 18 to prevent the support member 18 from moving longitudinally relative to the post members 22 and 24.

A protective cover 90 of paper, polyethylene, etc., as shown in FIG. 8, may be clamped over the flexible valve 10 to protect the valve against ozone attack.

In the modification of the present invention shown in FIG. 9, the support members are affixed to the chassis or engine and hence do not utilize post members affixed to the conduit. A fitting 68, which may serve as one of the support members, may be threaded into any convenient crankcase pressure source such as the oil separator 66. The tension on the valve member 10 may be altered by pulling the valve 10 further onto fitting 68 and holding the valve in the desired position with clamps 70 and 72. The conduit end 76 is affixed to the intake manifold with support bracket 74.

Although the present invention has been described with a certain degree of particularity, it is to be understood that the scope of our invention is not to be limited by the details set forth, but should be afforded the full breadth of the appended claims.

We claim:

1. In a crankcase ventilating system for internal combustion engines having an opening in the engine above the oil level through which blowby fluids can escape the engine and conduit means providing fluid communication between said opening and the induction system of said engine, said opening being subject to the crankcase pressure, said conduit means having a discontinuity therein with two open spaced apart conduit ends, and wherein flexible tubular valve means normally closed in response to manifold vacuum and adapted to open in response to pressure buildup in said crankcase to pass blowby fluids through said conduit means into said induction system are operably positioned between said conduit ends, the improvement comprising:

a frame apparatus for holding said conduit means in substantially axial alignment, and means associated with said frame apparatus for subjecting said tubular valve means to tension.

2. In a crankcase ventilating system for internal combustion engines having an opening in the engine above the oil level through which blowby fluids can escape the engine and conduit means providing fluid communica-

cation between said opening and the induction system of said engine, said opening being subject to the crankcase pressure, said conduit means having a discontinuity therein with two open spaced apart conduit ends, and wherein flexible tubular valve means normally closed in response to manifold vacuum and adapted to open in response to pressure buildup in said crankcase to pass blowby fluids through said conduit means into said induction system are operably positioned between said conduit ends, the improvement comprising:

a frame apparatus for holding said conduit means in substantially axial alignment, said frame member being mountable on said spaced apart conduit ends, and

means associated with said frame apparatus for subjecting said tubular valve means to tension.

3. In a crankcase ventilating system for internal combustion engines having an opening in the engine above the oil level through which blowby fluids can escape the engine and conduit means providing fluid communication between said opening and the induction system of said engine, said opening being subject to the crankcase pressure, said conduit means having a discontinuity therein with two open spaced apart conduit ends, and wherein flexible tubular valve means normally closed in response to manifold vacuum and adapted to open in response to pressure buildup in said crankcase to pass blowby fluids through said conduit means into said induction system are operably positioned between said conduit ends, the improvement comprising:

support means affixed to said spaced apart conduit ends, and a rigid post extending between said support means,

said support means being adapted for receiving said post, at least one of said support means being longitudinally movable on said post, whereby the longitudinal tension on said tubular valve may be varied.

4. In a crankcase ventilating system for internal combustion engines having an opening in the engine above the oil level through which blowby fluids can escape the engine and conduit means providing fluid communication between said opening and the induction system of said engine, said opening being subject to the crankcase pressure, said conduit means having a discontinuity therein with two open spaced apart conduit ends, and wherein flexible tubular valve means normally closed in response to manifold vacuum and adapted to open in response to pressure buildup in said crankcase to pass blowby fluids through said conduit means into said induction system is operably positioned between said conduit ends, the improvement comprising:

support means affixed to said spaced apart conduit ends, a rigid post extending between said support means,

said support means being adapted for receiving said post, at least one of said support means being longitudinally movable on said post, and means associated with said post for tensioning said tubular valve.

5. In a crankcase ventilating system for internal combustion engines having an opening in the engine above the oil level through which blowby fluids can escape the engine and conduit means providing fluid communication between said opening and the induction system of said engine, said opening being subject to the crankcase pressure, said conduit means having a discontinuity therein with two open spaced apart conduit ends, and wherein flexible tubular valve means normally closed in response to manifold vacuum and adapted to open in response to pressure buildup in said crankcase to pass blowby fluids through said conduit means into said induction system is operably positioned between said conduit ends, the improvement comprising:

support means affixed to said spaced apart conduit ends,

5

a rigid post extending between said support means, said support means being adapted for receiving said post, at least one of said support means being longitudinally movable on said post, and spring means positioned between said support means for tensioning said tubular valve.

6. In a crankcase ventilating system for internal combustion engines having an opening in the engine above the oil level through which blowby fluids can escape the engine and conduit means providing fluid communication between said opening and the induction system of said engine, said opening being subject to the crankcase pressure, said conduit means having a discontinuity therein with two open spaced apart conduit ends, and wherein flexible tubular valve means normally closed in response to manifold vacuum and adapted to open in response to pressure buildup in said crankcase to pass blowby fluids through said conduit means into said induction system is operably positioned between said conduit ends, the improvement comprising:

support means affixed to said spaced apart conduit ends,
a rigid post extending between said support means,
said support means being adapted for receiving said post,
at least one of said support means being longitudinally movable on said post,
spring means positioned between said support means for tensioning said tubular valve, and
means for varying the compression on said spring means.

7. In a crankcase ventilating system for internal combustion engines having an opening in the engine above the oil level through which blowby fluids can escape the engine and conduit means providing fluid communication between said opening and the induction system of said engine, said opening being subject to the crankcase pressure, said conduit means having a discontinuity therein with two open spaced apart conduit ends, and wherein flexible tubular valve means normally closed in response to manifold vacuum and adapted to open in response to pressure buildup in said crankcase to pass blowby fluids through said conduit means into said induction system is operably positioned between said conduit ends, the improvement comprising:

support means affixed to said spaced apart conduit ends,
a rigid post extending between said support means,
said support means being adapted for receiving said post,
at least one of said support means being longitudinally movable on said post, and
spring means positioned between said support means for tensioning said tubular valve, said post being threadably engaged with one of said support means whereby the amount of tension said spring exerts on said tubular valve may be limited and said limit varied.

8. The apparatus of claim 7 whereby said spring means are mounted around said post and extend between said support means.

9. In a crankcase ventilating system for internal combustion engines having an opening in the engine above the oil level through which blowby fluids can escape the engine and conduit means providing fluid communication between said opening and the induction system of said engine, said opening being subject to the crankcase pressure, said conduit means having a discontinuity therein with two open spaced apart conduit ends, and wherein flexible tubular valve means normally closed in response to manifold vacuum and adapted to open in response to pressure buildup in said crankcase to pass blowby fluids through said conduit means into said induction system is operably positioned between said conduit ends, the improvement comprising:

1

support means affixed to said spaced apart conduit

ends, a rigid post extending between said support means, said support means being adapted for receiving said post,

5 at least one of said support means being longitudinally
movable on said post,
10 spring means positioned between said support means
for tensioning said tubular valve, and
stop means on said post to limit longitudinal move-
ment of said support means relative to said post.

10. In a crankcase ventilating system for internal combustion engines having an opening in the engine above the oil level through which blowby fluids can escape the engine and conduit means providing fluid communication between said opening and the induction system of said engine, said opening being subject to the crankcase pressure, said conduit means having a discontinuity therein with two open spaced apart conduit ends, and wherein
15 flexible tubular valve means normally closed in response to manifold vacuum and adapted to open in response to pressure buildup in said crankcase to pass blowby fluids through said conduit means into said induction system is operably positioned between said conduit ends, the improvement comprising:
20
25

support means affixed to said spaced apart conduit ends,
a rigid post extending between said support means,
said support means being adapted for receiving said
post,
30 at least one of said support means being longitudinally
movable on said post,
spring means positioned between said support means
for tensioning said tubular valve, and
35 stop means on said post to limit longitudinal move-
ment of said support means relative to said post, said
post being fixed to one of said support means

40 11. In a crankcase ventilating system for internal combustion engines having an opening in the engine above the oil level through which blowby fluids can escape the engine and conduit means providing fluid communication between said opening and the induction system of said engine, said opening being subject to the crankcase pressure, said conduit means having a discontinuity therein with two open spaced apart conduit ends, and wherein
45 flexible tubular valve means normally closed in response to manifold vacuum and adapted to open in response to pressure buildup in said crankcase to pass blowby fluids through said conduit means into said induction system is operably positioned between said conduit ends, the im-
50 provement comprising:

support means affixed to said spaced apart conduit ends,
a rigid post extending between said support means,
said support means being adapted for receiving said
post,
at least one of said support means being longitudinally
movable on said post, said post being threadably en-
gaged with one of said supports and rotatable in
said other support.

60 12. In a crankcase ventilating system for internal combustion engines having an opening in the engine above the oil level through which blowby fluids can escape the engine and conduit means providing fluid communication between said opening and the induction system of said 65 engine, said opening being subject to the crankcase pressure, said conduit means having a discontinuity therein with two open spaced apart conduit ends, and wherein flexible tubular valve means normally closed in response to manifold vacuum and adapted to open in response to 70 pressure buildup in said crankcase to pass blowby fluids through said conduit means into said induction system is operably positioned between said conduit ends, the improvement comprising:

support means affixed to said spaced apart conduit ends,

7
a rigid post extending between said support means, said support means being adapted for receiving said post,

at least one of said support means being longitudinally movable on said post, said post at one end thereof being threadably engaged with one of said supports, the other end of said post having a reduced diameter along a portion of said post and rotatable within said support means at said reduced portion, said reduced section forming a shoulder adapted to bear against the support means to limit longitudinal movement between said post and said support means.

13. In a crankcase ventilating system for internal combustion engines having an opening in the engine above the oil level through which crankcase fluids can escape the engine and conduit means providing fluid communication between said opening and the induction system of said engine, said opening being subject to the crankcase pressure, said conduit means having a flexible tubular valve means therein, said valve means being normally closed in response to manifold vacuum and adapted to open in response to pressure buildup in said crankcase to pass blowby fluids through said conduit means into said induction system, the improvement comprising:

a one-way valve positioned in said conduit between 25 said flexible valve means and said induction system and being operable to pass fluids from said valve into said induction system and adapted to close said conduit to the passage of fluids between said induction system to said valve means.

14. The apparatus of claim 13 wherein said one-way valve is a swing check valve.

15. In a crankcase ventilating system for internal combustion engines having an opening in the engine above the oil level through which blowby fluids can escape the engine and conduit means providing fluid communication between said opening and the induction system of said engine, said opening being subject to the crankcase pressure, said conduit means having a discontinuity therein with two open spaced apart conduit ends, and 35 wherein flexible tubular valve means normally closed in response to manifold vacuum and adapted to open in response to pressure buildup in said crankcase to pass blowby fluids through said conduit means into said induction system is operably positioned between said conduit ends, the improvement comprising:

a pair of support means affixed to said spaced apart conduit ends,

a rigid post extending between said support means, said support means being adapted for receiving said 50 posts,

at least one of said support means being longitudinally movable along said post whereby the longitudinal tension on said tubular valve positioned between said support means may be varied, said support means support positioned between said induction system and said tubular valve having valve means therein adapted to close said conduit against the passage of fluids from said induction system to said tubular valve.

16. A frame apparatus to support a flexible tubular valve positioned in a conduit extending between the crankcase and the induction manifold of an internal combustion engine, said conduit having a discontinuity therein with two spaced apart conduit ends, comprising:

a pair of support means affixed to spaced apart conduit ends,

8
a rigid post extending between said support means, said support means being adapted for receiving said post, at least one of said support means being longitudinally movable on said post at one end thereof, said post at the other end being threadably engaged with the other support means whereby the longitudinal tension on said tubular valve member may be varied.

17. A frame apparatus to support a flexible tubular valve positioned in a conduit extending between the crankcase and the induction manifold of an internal combustion engine, said conduit having a discontinuity therein with two spaced apart conduit ends, comprising: support means affixed to said spaced apart conduit ends and spring means positioned between said support means whereby to maintain said tubular valve in tension.

18. A frame apparatus to support a flexible tubular valve positioned in a conduit extending between the crankcase and the induction manifold of an internal combustion engine, said conduit having a discontinuity therein with two spaced apart conduit ends, comprising:

support means affixed to said spaced apart conduit ends, a rigid post extending between said support means, said support means being adapted for receiving said post, said post being longitudinally slidable through one of said support means and threadably engaged with the other of said support means, spring means around said post adapted to maintain a constant tension on said tubular valve, the longitudinal limit of said spring means being variable with said threadable post.

19. A crankcase ventilating system for internal combustion engines, comprising in combination:

an opening in the crankcase above the oil level through which crankcase fluids can escape the crankcase, an opening in the intake manifold, conduit means connecting said crankcase opening with said intake manifold opening,

a flexible tubular valve positioned in said conduit means and having the inner walls of said tubular member preformed in a substantially closed manner along a transverse portion of said tubular member and having a capillary opening through said closed portion, said tubular member being normally substantially closed in said preformed closed portion by intake manifold vacuum, said tubular member being adapted to open in response to crankcase pressure buildup in said crankcase to pass fluids through said conduit means into said intake manifold, said capillary opening being of a size to prevent the passage of sufficient blowby fluids into the crankcase manifold to result in substantial power loss, and

a second conduit extending between the clean side of the air filter of said engine and said crankcase whereby clean air is drawn into said crankcase by induction manifold vacuum imposed on said crankcase through said tubular valve.
